UNITED STATES PATENT OFFICE.

JAMES C. POTTER, OF PAWTUCKET, RHODE ISLAND, ASSIGNOR TO
AMERICAN SPINDLE COMPANY, OF PAWTUCKET, RHODE ISLAND,
A CORPORATION OF RHODE ISLAND.

SPINDLE.

No. 821,884.

Specification of Letters Patent.

Patented May 29, 1906.

Application filed September 23, 1904. Serial No. 225,630.

To all whom it may concern:

Be it known that I, JAMES C. POTTER, of Pawtucket, in the county of Providence, and in the State of Rhode Island, have invented 5
a certain new and useful Improvement in
Spindles; and I do hereby declare that the following is a full, clear, and exact description
thereof, reference being had to the accompanying drawing, in which the figure is a vertical 10
longitudinal sectional view of a spindle
embodying my invention.

The object of my invention has been to provide a spindle embodying the invention which is the subject of Letters Patent granted 15
upon my application to the American Spindle Company, of Pawtucket, Rhode Island, for spinning-spindles, August 18, 1903, No. 736,544, in which no spring or weight shall be used, but in which fluid-pressure 20
sure shall be used to serve the function of the spiral spring in my aforesaid patent, and to such ends my invention consists in the spindle hereinafter specified and claimed.

In carrying my invention into practice I provide a bolster-case A having a bolster B journaled therein, the bolster having a shoulder b at its upper end which bears upon the upper end of the bolster-case. The lower end of the bolster is preferably reduced in diameter and a shell D is secured to such end, as by a pin E. The shell is provided with a conical seat d, in which is mounted the spherical upper end F of a rod G, which latter extends through openings in the lower end of the said shell and in the lower end of the bolster-case. A shell G' is secured to the lower end of the bolster-case by any form of oil-tight joint, and a piston H, secured to the lower end of the rod G, fits loosely within said shell. A valve or valves are formed in the piston, as by tapered plugs I seated in tapered holes h. The plugs I may, if desired, have stems i, in which are secured removable pins i', so as to prevent their escaping from the holes h'. A yielding body, such as oil, is interposed between the bolster and the bolster-case, and the shell G' and bolster-case are filled with oil or other fluid.

In the operation of my spindle-bearing

upon the principle of my aforesaid patent 50
the bolster seeks to move laterally in order to place the axis of revolution of the spindle in line with the center of gravity of the weight being carried. This causes a slight rising of the piston, and as the valves open upwardly 55
the body of oil above the piston can only reach the lower side of the piston, which it must do to permit the piston to rise, by passing between the piston and the oil-shell. This space is made sufficiently small so that 60
the proper resistance is secured. When the bolster straightens up again, the piston simply sinks through the oil, the oil rising through the holes h and slightly lifting the conical 65
plugs.

It is obvious that various changes can be made in the above-illustrated construction which will be within the scope of my invention, and I do not desire to limit myself beyond the requirements of the prior art and 70
the letter of my claims.

Having thus described my invention, what I claim is—

1. In a spindle-bearing, the combination of a bolster, a bolster-case, a piston secured 75
to the lower end of the bolster-case, and means for offering resistance to the upward movement of the piston while permitting a free downward movement thereof.

2. In a spindle-bearing, the combination 80
of a bolster, a bolster-case, a rod jointedly secured to the lower end of the bolster-case, a piston secured to said rod and loosely fitting the bolster-case, and valves in said piston.

3. In a spindle-bearing, the combination 85
of a bolster, a bolster-case, a rod jointedly secured to the lower end of the bolster, a piston secured to said rod, and loosely fitting the bolster-case, and valves in said piston consisting of conical plugs seated in conical 90
openings.

In testimony that I claim the foregoing I have hereunto set my hand.

JAMES C. POTTER.
